CHEST OF DRAWERS

Ernest Herrman, Hillsdale, N. J., and William J. Carr, Gardner, Mass., assignors to Heywood-Wakefield Company, Gardner, Mass., a corporation of Massachusetts

Application August 18, 1952, Serial No. 21,083

Term of patent 3½ years

(Cl. D33—19)

To all whom it may concern:

Be it known that we, Ernest Herrman, a citizen of the United States and a resident of Hillsdale, county of Bergen, and State of New Jersey, and William J. Carr, a citizen of the United States and a resident of Gardner, county of Worcester, and State of Massachusetts, have invented a new, original, and ornamental Design for a Chest of Drawers, of which the following is a specification, reference being had to the accompanying drawing forming a part thereof, in which:

Fig. 1 is a perspective view of a chest of drawers showing our new design; and

Fig. 2 is a horizontal sectional view through the chest as taken on the line 2—2 of Fig. 1.

We claim:

The ornamental design for a chest of drawers, substantially as shown.

ERNEST HERRMAN.
WILLIAM J. CARR.
